I claim, the ornamental design for an electronic device, as shown and described.

DESCRIPTION

FIG. 1 is the front perspective view of an electronic device showing my new design;

FIG. 2 is a front elevation view thereof;

FIG. 3 is a rear elevation view thereof;

FIG. 4 is a side elevation view thereof;

FIG. 5 is another side elevation view thereof;

FIG. 6 is a top plan view thereof; and,

FIG. 7 is a bottom plan view thereof.

The broken lines depict portions of the electronic device that form no part of the claimed design.
